UNITED STATES PATENT OFFICE.

LOUIS J. CRECELIUS, OF ST. LOUIS, MISSOURI.

RAILWAY TRACK-DRILL.

SPECIFICATION forming part of Letters Patent No. 375,669, dated December 27, 1887.

Application filed May 5, 1887. Serial No. 237,258. (No model.)

To all whom it may concern:

Be it known that I, LOUIS J. CRECELIUS, of St. Louis, Missouri, have made a new and useful Improvement in Railway Track-Drills, of 5 which the following is a full, clear, and exact description.

The leading features of this improvement are: the construction of the drill-brace whereby combined strength and lightness and an 10 easily-manipulated tool are obtained; making the drill in feeding to move longitudinally through the stock, which meanwhile remains stationary so far as longitudinal movement is concerned; supporting the ratchet and parts 15 immediately therewith connected in a frame, which in turn at its outer end is journaled upon the brace, so that it not only can be adjusted laterally therein, but also to be turned vertically thereon to point the drill in the plane of 20 the brace or at an angle therewith; the automatic feed; the provision for elevating the working parts, so that they shall clear the tie above which the drill is being used.

Other features will appear in the description, and be noted in the claims.

In the annexed drawings, making part of this specification and exhibiting the most desirable mode of carrying out the improvement, Figure 1 is a plan of the improved tool, the 30 drill not being shown. Fig. 2 is a view in perspective of the tool in position. Fig. 3 is a cross vertical section on the line 3 3 of Fig. 1, and including the drill and rail. Fig. 4 is a section upon an enlarged scale on the line 4 4 35 of Fig. 3. Fig. 5 is a view in perspective of the ratchet. Fig. 6 is a view in perspective of the feed-screw. Fig. 7 is a view in perspective of the sleeve which encircles the ratchet-spindle. Fig. 8 is a view in perspective 40 of the feed-nut. Fig. 9 is a view in perspective of the friction-plate between the feed-nut and the feed-wheel, which last-named part is shown in perspective in Fig. 10. Fig. 11 is a vertical section on the line 11 11 of Fig. 1. Fig. 12 is a vertical section on the line 12 12 of 45 Fig. 3, and Fig. 13 is a vertical section on the line 13 13 of Fig. 3.

The same letters of reference denote the same parts.

50 A represents the brace or main frame of the tool. In outline it is substantially of the

customary form, it being composed of the two end bars, a a' , and the main bar a^2 , the end bars at a^3 being hook-shaped to engage with the rail B, Figs. 2 and 3, and the main bar being attached to the end bars at a sufficient distance from the rail for the working parts of the tool to be included between the main bar and the rail. Instead, however, of the parts a a' a^2 55 being solid, they are preferably tubular, as thereby the construction is rendered much lighter—a matter of concern, for in use the track-drill is required to be carried along the track from place to place, and whatever tends to diminish the weight of the tool is desirable; 60 but the main bar a^2 , by reason of its being tubular, is also greatly stiffened in proportion to its weight, and as this part of the brace is required to sustain the thrust of the drill the brace is improved by making the part tubular; and by making all three parts tubular the 65 brace not only can be readily and cheaply manufactured from pipes easily procurable, but they (the bars a a' a^2) are adapted to be readily united by means of detachable connections—namely, the elbows a^4 —for, as will be 70 presently referred to, the end bars need to be separated from the main bar when the drill-operating mechanism is removed from the brace. The elbows a^4 also serve to strengthen 75 the brace more than would a simple bead in a tubular bar at the points where the main and end bars are united.

C represents the frame containing the mechanism for operating the drill D, Figs. 2 and 3. 85 By making its outer end, say, in the form of the sleeve c, it is attached to the main bar a^2 , so that the frame can be revolved thereon, and also that it can be slipped thereon from end to end of the brace. After it has been adjusted into 90 the desired position, it can be clamped b means of the set-screw c'. The frame is angled at c^2 to admit the drill rotating and feeding mechanism.

E represents the ratchet. It is attached to 95 or made in one piece with the tubular spindle E', which is journaled at e in the frame C and upon the opposite side of the ratchet is extended at e'.

F represents the customary ratchet-lever, 100 journaled by means of the sleeve f upon the ratchet-spindle at e', and it is adapted to co-

operate with the ratchet in the ordinary manner.

The drill D, instead of simply being chucked in the spindle E', is adapted to be passed thereinto almost its entire length, as indicated by the broken lines in Fig. 3. To this end the spindle E' is perforated throughout its length, and by this means the drill is held so steadily in its holder as to prevent it from wobbling—a difficulty experienced with the drills now in use—and in consequence of its being thus held the hole drilled conforms more closely in diameter to the drill, and the drilling operation is more easily and accurately performed. But, further, and especially, this advantage is obtained: the ratchet-spindle, which constitutes the stock, so far as longitudinal movement is concerned, remains stationary, while the drill is fed longitudinally through the ratchet-spindle. By this means the drill at the start can be set nearly its length back into the stock and the stock can be set in close proximity to the part being drilled, and by the time the drill is any distance out of the stock the drill-point has been entered into the part being drilled. The stock can thus be held perfectly steady in the drill-frame, and the drill is always well held either wholly in the stock or in the stock in combination with the part being drilled. The drill can be fed by any suitable means. I have, however, devised an automatic feed, which forms part of this improvement, and which will be described.

G represents a feed-screw or follower in the rear of and preferably abutting directly against the drill. It is adapted to work partly in the ratchet-spindle and partly in the tubular portion c³ of the frame C. Its threaded portion g is squared to cause the screw to rotate with the ratchet-spindle, whose perforation e², in which the drill and screw are received, is also squared. The portion g' of the screw or follower is provided with a shoulder, g², to prevent the screw from being worked out of the part c³, the shoulder, when the screw has been moved out as far as desired, coming against the hub h of the feed-wheel H.

The screw portion g' is rounded to enable it to act as a journal to turn steadily in the part c³ as the ratchet mechanism, drill, and screw are rotated. The feed-wheel H is arranged between the ratchet-spindle and the frame part c³, and is threaded and made to engage with the feed-screw; but when the feed-wheel is held stationary it acts as a nut to effect the feeding forward of the feed-screw, which then in turn acts as a thrust-bolt to feed the drill.

The preferable mode of operating the wheel H is as follows: I represents a nut adapted to be screwed on the hub h of the wheel H toward and from the part h' of the wheel, the movement being indicated by the broken lines in Fig. 3. J represents a plate arranged between the nut I and wheel part h', and having an extension, j, Figs. 1, 2, and 9, which, say by inserting it in an opening, c⁴, in the frame

C, serves to hold the plate J from being turned around with the wheel H. By screwing the nut I against the plate J and thereby pressing the plate against the wheel part h', the plate acts as a brake and the wheel H becomes locked to the plate J, and as long as it remains locked the drill feeds. The mechanism can, by means of the nut I, be adjusted to cause the drill to feed against a lesser resistance and to yield against a greater resistance, and according as the nut I is tightened is the point at which the brake upon the wheel ceases to act. The plate J is preferably of springy material, is made to encircle the wheel-hub, and is slit at j', and the wheel part h' is preferably chambered out at h² to receive the central portion of the plate J when it is pressed against the wheel part. By means of the ratchet-spindle and the screw the ratchet mechanism is in effect journaled at two points in the frame C—namely, at c and c³.

Another object of the improvement is to provide a tool which is wholly self-contained, so that when transported it can be handled as a single piece. It is seen that the drill-operating mechanism is secured in the frame C, and that the frame is fastened to the brace, and when it is desired to secure the frame it is turned into the plane of the brace and the ratchet-lever is brought down to a bearing upon the end bar, and then, by means of the keeper K, which is pivoted to the end bar, so that it can be turned around thereon, as indicated in the drawings, it (the ratchet-lever) is secured, so that the entire device is brought into and held in a compact form, as shown in Fig. 1.

As the drill has frequently to be used directly over a tie, L, Fig. 2, the tool is provided with a leg, M, which serves to uphold the brace sufficiently for the drill-operating mechanism to clear the tie and be free to be worked. The leg is preferably an extension of the sleeve c. The screw cannot be moved outward in the frame part c³ so far as to be disengaged from the feed-wheel H. This is preferably accomplished by proportioning the parts so that the outer end of the screw encounters the main bar a² before the other end of the screw passes the feed-wheel.

When it is desired to remove the feed-screw and to detach the parts of the ratchet mechanism, as in case of repair, the brace A is dissected by separating an end bar from the main bar a² and then slipping the frame C off the main bar, whereupon the feed-screw can be withdrawn through the opening c⁵, Fig. 3, from the frame.

I desire not to be confined to what is termed a "railway track-drill" in applying several of the above-described features.

I claim—

1. In combination, a suitable supporting-frame, the drilling-tool, the ratchet-wheel carrying said tool, a ratchet-spindle for rotating the same, and means operated by the ro-

tation of the ratchet for automatically moving the drilling-tool longitudinally, substantially as described.

2. In combination, the supporting-frame C, a holder, as E, for the drilling-tool having rotary movement only in said frame, and means within the holder for automatically moving the drilling-tool longitudinally, substantially as described.

10 3. In combination, the supporting-frame having a hollow portion, c^3 , tool-holder, as E, supported in said frame, and having a hollow spindle, and means for giving the tool longitudinal movement, said means being located 15 within the hollow spindle and the hollow portion of the frame, substantially as described.

4. In combination, the drilling-tool, a rotary holder, E, therefor, the follower in the rear of the tool, independent thereof, operated 20 by the revolution of the holder to give longitudinal movement to the tool, and a controlling-nut in connection with the follower for regulating the movement of the said follower, substantially as described.

25 5. The combination, in a track-drill, of the main bar and the drill-frame C, said drill-frame being journaled upon said main bar to be rotated thereon, as described.

6. In a track-drill, the main bar, the drilling 30 mechanism, and a frame, as C, for supporting said mechanism, said frame having a journal-bearing at its end adapted to the main bar and to have sliding movement thereon, substantially as described.

35 7. In combination, the main bar, the drilling mechanism, the frame for supporting the same, said frame having a tubular journal-bearing at its end adapted to the bar, and a set-screw, substantially as described.

40 8. In combination, the brace-frame composed of the bar A and end bars, a a' , a drilling mechanism, a drill-frame for supporting said mechanism carried by the main bar, and arranged, when in its normal position, to lie 45 in the same plane with the brace-frame, substantially as described.

9. In combination, the main bar A, the drilling mechanism, the frame C, for supporting said mechanism, the ratchet-lever F, the end bar, a , and a keeper, K, on said arm, adapted 50 to hold the lever F, substantially as described.

10. The combination, in a track or other drill, of the perforated ratchet-spindle, the perforated frame part c^3 , the drill D, and the screw G, substantially as described. 55

11. The combination of the brace, the drill-frame, the screw, the wheel H, the nut I, and the plate J, substantially as described.

12. The combination of the drill, the screw, the ratchet and spindle, the frame C, the brace, 60 the wheel H, the nut I, the plate J, and the ratchet-lever, substantially as described.

13. The combination of the ratchet-spindle having the squared perforation and the screw having its threaded portion squared, as described. 65

14. The combination of the screw having the shoulder, the wheel H, and the drill-frame part c^3 , as described.

15. The combination of the screw, the wheel 70 H, the drill-frame part c^3 , and the main bar a^2 , as described.

16. The combination of the drill-frame C, the ratchet-spindle, and the screw, as described, and for the purpose of supporting said ratchet-spindle at both ends. 75

17. The drill-frame C, perforated at c^3 and c^5 , in combination with the screw and the drill-brace A, substantially as described.

18. In combination, the brace-frame, the 80 drilling mechanism, and a leg, M, for supporting the brace-frame and said drilling mechanism, substantially as described.

19. The combination of the drill D, the perforated ratchet-spindle, and the screw G, said 85 screw acting to push the drill longitudinally through the spindle, as described.

LOUIS J. CRECELIUS.
